HOSIERY INSPECTION DEVICE

Edmund J. Butler, Cordele, Ga., assignor to Maywood Hosiery Mills, Inc., a corporation of Georgia

Application November 23, 1948; Serial No. 61,629

5 Claims. (Cl. 223—39)

1

This invention relates to hosiery inspection devices, and more especially to a device of this sort particularly adapted for use in the inspection of full fashioned hosiery.

In the manufacture of hosiery, particularly full fashioned hosiery, one of the most troublesome difficulties is the problem of avoiding "pull-threads" during the knitting operation and subsequent handling of the knitted stockings. "Pull-threads" is the term commonly used to describe the defect which results in the stocking structure when one of the threads is kinked or drawn out of place.

This defect is often caused in process of inspecting the stockings because the stockings, being formed inside out, are turned or reversed for inspection and the attrition on the body of the stocking as it is reversed is a likely source of pull-threads. This is particularly true of full fashioned hosiery which are formed with a seam that can exert a rather severe rubbing action on the body of the stocking during reversal.

According to the present invention this difficulty is avoided by employing an inspection device in which the inspection form comprises a channel-shaped body proportioned to receive and support a stocking extended to full length, and a web portion extending between the top edges of the channel-shaped body adjacent the turning or reversing nose thereof but spaced from this nose so that it defines an opening through which a stocking extended interiorly in the channel-shaped body may be drawn for reversal over the nose and extended exteriorly on the body for inspection. By this arrangement the turned portion of the stocking is spaced at all times from the unturned portion thereof so that all attrition between the stocking portions is eliminated during reversal, and rubbing of the body of the stocking by the seam in particular is avoided.

The present invention is described more in detail below in connection with the accompanying drawing in which:

Fig. 1 is a top plan view of a hosiery inspection device constructed in accordance with the present invention;

Fig. 2 is a corresponding side view, partly in section, of the hosiery inspection device shown in Fig. 1;

Fig. 3 is a section taken on the line 3—3 in Fig. 1;

Fig. 4 is a section taken on the line 4—4 in Fig. 1;

Fig. 5 is a view similar to Fig. 1 illustrating

2

the manner in which the stocking turning operation is started;

Fig. 6 is a view similar to Fig. 5 showing a further stage of the stocking turning operation; and,

Fig. 7 is a fragmentary plan view showing the stocking completely turned and partly withdrawn from the inspection device.

Referring now to the drawing in detail, and more particularly at first to Figs. 1 to 4, inclusive, the hosiery inspection device illustrated is designated generally by the reference numeral 10, and as shown comprises an inspection form 12 adapted to be supported at one end in any suitable manner, as by the spindle 14 and bearing bracket 16, and arranged with a reversing nose 18 and its other free end;

The inspection form 12 has a channel-shaped body proportioned to receive interiorly as at 20 a stocking S extended to full length with the welt W thereof disposed adjacent the reversing nose 18 and the toe T extended toward the supported end of the inspection form 12. The inspection form 12 is further formed with a web portion 22 extending between the top edges of its channel-shaped body adjacent the reversing nose 18 but spaced therefrom so that it defines an opening 24; as previously noted, through which the stocking S may be drawn welt first for reversal over the nose 18 and extended exteriorly over the form 12 for inspection;

It will be further noted that the reversing nose 18 extends in the nature of a lip or flange at the free end of the inspection form 12 (compare Figs. 1 and 2). This extending lip arrangement of the reversing nose 18 makes it possible in extending the stocking S over the form 12 for inspection, to arrange the toe T of the stocking S so that the looper line in the toe T is disposed across a face of the nose 18 and is thereby made clearly visible to an inspector in normal inspection position beside the form 12. Also, with this arrangement the fabric at the toe T is stretched so that any weakness or defect at the looper line is made clearly apparent. Heretofore it has been necessary, with the round nose inspection forms commonly in use, for the inspector to shift position for inspection of the looper line, or to provide mirrors for viewing a reflection of the looper line from the inspection position, both of which expedients are not only more troublesome but also considerably less efficient than the easy direct viewing of the looper line made possible by the form of reversing nose 18 of the present invention.

55 The manner in which this operation is carried

out is illustrated in Figs. 5 to 7 of the drawing. In Fig. 5, the welt W of the stocking S is shown in the process of being drawn through the opening 24 and trained over the reversing nose 18. The reversal of the stocking S is continued by drawing the welt W exteriorly over the inspection form 12 as indicated in Fig. 6 until the stocking S is fully extended exteriorly on the form 12 for inspection. As this is done the turned portion of the stocking S is maintained exteriorly on the form 12 in spaced relation to the unturned portion still supported interiorly in the channel shaped body at 18, so that all rubbing or attrition between the stocking portion during reversal is eliminated. After full reversal and inspection, the stocking S is removed from the form 12 toe first and the operation is repeated with a succeeding stocking. The hosiery inspection device of the present invention is accordingly adapted for inspection of hosiery in the usual manner, but provides for handling the hosiery during inspection so that the tendency to induce pull threads is avoided while still allowing the operation to be carried out easily and efficiently. In the usual case, the device is preferably arranged so that the inspection form 12 is disposed horizontally as illustrated in the drawing, but it may also be used advantageously in other positions where it is desired to combine other operations, such as mending, with the inspection operation.

I claim:

1. A hosiery inspection device comprising an inspection form of the type incorporating a reversing nose, said form having a channel-shaped body proportioned for receiving and supporting interiorly a stocking extended to full length, and formed with a web portion extending between the top edges of said body adjacent the nose thereof but spaced from said nose and thereby defining an opening through which a stocking extended interiorly in said channel-shaped body may be drawn for reversal over said nose and extended exteriorly on said body for inspection.

2. A hosiery inspection device comprising an inspection form adapted to be supported at one end and arranged with a reversing nose at its other free end, said inspection form having a channel-shaped body proportioned for receiving and supporting interiorly a stocking extended to full length and being formed with a web portion extending between the top edges of said body adjacent said nose but spaced therefrom and thereby defining an opening through which a stocking extended interiorly in said channel-shaped body may be drawn for reversal over said nose and extended exteriorly on said body for inspection.

3. In a hosiery inspection device, an inspection form supported horizontally at one end and arranged with a reversing nose at its other free end, said inspection form having a channel-

shaped body proportioned for receiving and supporting interiorly a stocking extended to full length and being formed with a web portion extending between the top edges of said body adjacent said nose but spaced therefrom and thereby defining an opening through which a stocking extended interiorly in said channel-shaped body may be drawn welt first for reversal over said nose and extended exteriorly on said body for inspection with the body of said stocking spaced at all times to avoid rubbing by the seam thereof.

4. A hosiery inspection device particularly adapted for avoiding pull threads in the inspection of full fashioned hosiery, comprising an inspection form supported horizontally at one end and arranged with a reversing nose at its other free end, said inspection form having a channel-shaped body proportioned for receiving and supporting interiorly a stocking extended to full length with the welt thereof disposed adjacent said nose, and said inspection form being further formed with a web portion extending between the top edges of said channel-shaped body adjacent said nose but spaced therefrom and thereby defining an opening through which a stocking extended interiorly in said channel-shaped body may be drawn welt first for reversal over said nose and extended exteriorly on said body for inspection with the body of said stocking spaced at all times to avoid rubbing by the seam thereof.

5. A hosiery inspection device comprising an inspection form having a channel-shaped body proportioned for receiving and supporting interiorly a stocking extended to full length, said body being adapted for support at one end and being formed with a reversing nose at its other free end, said body being further formed with a web portion extending between its channel edges adjacent said reversing nose but spaced from said nose and thereby defining an opening through which a stocking extended interiorly in said channel-shaped body may be drawn for reversal over said nose and extended exteriorly on said body for inspection, and said reversing nose being formed in the nature of an extending lip at the free end of said body whereby the looper line in the toe of a stocking extended over said body for inspection may be disposed across a face of said nose for direct viewing in normal inspection position beside said form.
